UNITED STATES PATENT OFFICE.

JOHN WOLF, OF ALLEGHENY CITY, PENNSYLVANIA.

BOOT-CLEANER.

SPECIFICATION forming part of Letters Patent No. 294,834, dated March 11, 1884.

Application filed December 10, 1883. (No model.)

To all whom it may concern:

Be it known that I, JOHN WOLF, a citizen of the United States, residing at the city of Allegheny, in the county of Allegheny and State of Pennsylvania, have invented a new and useful Improvement in Boot-Cleaners, of which the following is a specification.

The nature of my invention consists of an iron plate, upon one side of which is arranged a scraper and on the other side a brush, which plate is so pivoted in suitable standards as that it may be turned over to bring either the brush or scraper uppermost by simply raising the plate a short distance to release it from its bearings, which are so constructed as to hold the brush or scraper firmly in proper position when in use, yet allow either to occupy the place of the other, if and as required.

The construction and operation of my combined pivotal foot-scraper and brush will be readily understood from the following description, taken in connection with the accompanying drawings, wherein—

Figure 1 represents a front elevation of my combined pivotal foot-scraper and brush. Fig. 2 is a top view, and Fig. 3 an end elevation, of the same.

To put my invention into practice, I provide an oblong metallic plate, *a*, lengthwise upon one side of which is rigidly affixed an ordinary scraper, *b*, and on the other side a suitable brush, *c*. Each end of said plate *a* is furnished with a stout rectangular pindle or trunnion, *d*, broader or thicker in one direction than the other, and each pindle *d* is sup-

ported in a key-hole-shaped slot, *e*, formed in the upper portion of a substantial frame, *f*, so that when the brush *c* is brought to the requisite position for operation the narrowest part of each pindle will come opposite and fall into the contracted portion *g* of its respective slot, being thereby temporarily prevented from further rotation; but by lifting the plate its pintles *d* will be correspondingly raised, and when in the enlarged or circular portion *h* of the slots are free to turn therein in either direction, yet by reason of their shape are kept from falling back into the contracted portion of the slots until the narrow side of each pindle is directly opposite thereto. So, if the brush is uppermost, by simply raising the plate sufficiently to free its trunnions, the brush may be turned down and the scraper brought to occupy its place, or vice versa.

Having thus described my invention, I claim—

A new and improved foot-scraper consisting of the oblong metallic plate *a*, having on one side thereof a scraper, *b*, and on the other side a brush, *c*, and at each end a rectangular pindle or trunnion, *d*, broader or thicker in one direction than the other, in combination with the supporting-frame *f*, having the key-hole-shaped slots *e*, as shown and set forth.

JOHN WOLF.
